UNITED STATES PATENT OFFICE.

WILLARD C. JAMES, OF CUCAMONGA, CALIFORNIA.

APARTMENT-HOUSE.

SPECIFICATION forming part of Letters Patent No. 700,501, dated May 20, 1902.

Application filed June 17, 1901. Serial No. 64,947. (No model.)

To all whom it may concern:

Be it known that I, WILLARD C. JAMES, a citizen of the United States, residing at Cucamonga, in the county of San Bernardino and State of California, have invented new and useful Improvements in Apartment-Houses, of which the following is a specification.

This invention is applicable as a house having many living-apartments and comprises a compartment-section for housekeeping purposes and also adapted to be made in a small size to be sold as a toy for children's play-houses. Said compartment-section is also adapted to be manufactured for use as a part of a tent-house for camping at the beach and elsewhere with home comforts.

An object of this invention is to provide in the most compact and convenient form a house affording all the necessary conveniences and facilities for housekeeping—that is to say, by my invention a single apartment is made to satisfactorily serve as parlor, sitting-room, kitchen and pantry, dining-room, two bed-rooms, bath-room, store-room, and library, the apartment being adapted for practically instantaneous transformation from parlor to dining-room, kitchen, bath-room, or bed-room, or from either one of these several rooms into the others, respectively.

An object of this invention is, furthermore, to allow a portion of a small apartment to be used as a bath-room or bed-room by one person with perfect privacy, while the other portion of the apartment is used with like privacy by another person as a bed-room, sitting-room, library, or parlor.

In its amplified form this invention also includes an apartment-house comprising a front and back parlor, the front parlor being adapted for use as a bed-room as well as a parlor and affording, when used as a parlor or sitting-room, access to either of the two rooms into which the back parlor can be transformed, thus affording perfect privacy to the occupants of both of the rooms into which the back apartment is transformed, also giving to the occupants of the rear bed-room and the front bed-room equal private access to the bath-room from their respective rooms without one interfering with the other, at the same

time maintaining the privacy between the bath-room and both of the bed-rooms.

Another object of this invention is to make provision for the construction of a building containing a large number of double apartments, such as above mentioned, with the greatest economy of space and material and to furnish each of the apartments with suitable plumbing at the lowest expense.

Another object of this invention is to provide a substantial side for a tent-house, which side will furnish the occupant of the tent with the housekeeping facilities above referred to.

In carrying out this invention a portion of the apartment may be factory-made and all of the parts may be machined out. This is true of both the large size and the toy size, and it is to be understood that the dimensions of the large or living size and the dimensions of the small or toy size may be respectively varied without departing from this invention.

An object of this invention is to make provision whereby a couple of persons of moderate means will be enabled to make their home in apartments elegantly finished in mahogany, rosewood, or other expensive materials and be able to lodge their guests comfortably, also to dispense with numerous rooms and thereby to lighten the labor of housekeeping, 75

so as to enable the housewife to dispense with a servant—that is to say, a woman who would not be able without a servant to take care of six rooms, for instance, might be readily able 85 to take care of two rooms without assistance, and by this invention I combine within two rooms the functions and conveniences of six rooms and also enable the housewife at short notice and with slight labor to transform her 90 rooms from toilet, kitchen, and bed-room uses to a presentable condition for receiving visitors. Provision is made for the utilization of ordinarily wasted space by supplying storage facilities in the floor between the 95 floor-joists, thus supplying the occupants of the apartments with an ice-chest and with a cedar chest for furs and the like without occupying any space that is ordinarily of use.

A further feature of this invention is the 100 provision for airing the bed-clothes, also for cooling water and preserving food in dry

climates, also for ventilating the kitchen and the bed-room and closet.

The invention includes the apartment-house as a whole and the compartment-section, which may or may not be made as a separate article of manufacture of toy size or of living size, as desired, to be used separately for a tent-house, if required, or to be permanently set into a building to form part of an apartment-house, or to be built in the building at the time of constructing the building.

The invention also includes various features, parts, and combinations of parts herein particularly set forth.

15 The accompanying drawings illustrate the invention.

Figure I is a plan view of an apartment-house embodying my invention. Fig. II is a fragmental view of the same on an enlarged scale. Fig. III is a view on a small scale of one of the compartment-sections as a separate article of manufacture for use as a toy when made on a small scale and for use for a tent-house or an apartment-house or a knock-down house when made on a large scale. Fig. IV is a fragmental sectional plan showing in detail the completed partition with plumbing for a pair of double apartments. Fig. V is a perspective view of one side of a back 25 parlor in an apartment-house embodying this invention. Fig. VI is a view of the same when arranged for use as a bed-room and library and partially prepared for use as a bath-room. Fig. VII is a perspective fragmental detail of the bath-room or toilet when 30 the washstand is ready for use. Fig. VIII is a perspective fragmental detail showing the use of the bath-tub in connection with the clothes-rack and cot-frame serving the office 35 of a bed. Fig. IX is a fragmental perspective detail of the clothes-closet with the combined cot-frame and clothes-rack in position therein ready for use as a clothes-rack. Fig. X is a fragmental perspective detail 40 showing the table-chair in position for removing the door-panel for use in connection with said table-chair to form a dining-table. Fig. XI shows the dining-table ready for use having the door-panel thereon as a table-top.

45 Fig. XII is a vertical sectional detail showing the table-chair in position for removing the door-panel from the kitchen-door to form the top of the dining-table shown in Fig. XI.

50 Fig. XIII is a sectional detail on line XIII, Figs. II, V, and VI, cutting through the toilet-compartment and showing the wash-stand, bath-tub, bath-tub drain, and window-seat in vertical mid-section. Fig. XIV is a section on line XIV, Figs. II and VI.

55 Fig. XV is a fragmental perspective detail interior view of the kitchen and pantry compartment. Fig. XVI is a fragmental section on line XVI, Fig. II, showing the partition-curtain outdrawn and secured by its upright 60 bar to the middle wall between the front and rear apartments to form two rooms of the rear apartments. Fig. XVII is an enlarged

detail showing the upper fastening for the partition-curtain.

65 1 indicates in a general way a compartment-section for a house, comprising a case 2, divided by partitions 3 4 5 to form at one end a toilet-compartment 6 and at the other end a secretary, clothes and cot-storing closet 7, and between the toilet-compartment and 70 the closet a bed-holding compartment 8 and a kitchen and pantry compartment 9.

75 10 indicates a bath-tub of greater length than the depth of the toilet-compartment, mounted in said toilet-compartment to slide 80 out and in and projecting outward from said compartment when slid in, thus to utilize the compartment for concealing the bath-tub in such part as is practical with a compartment of economical depth.

85 11 indicates a combined clothes-rack and cot-frame interchangeably mounted in the closet 7 to there serve as a clothes-rack and on top of the outdrawn bath-tub 10 to there serve as a bed, said rack being thus adapted for interchangeable use as a clothes-rack and bed. 12 indicates a bed pivoted in the bed-holding compartment 4. An upright curtain 13 is mounted in the compartment-section 1 to be drawn out to form a partition in any apartment of 90 which the front face 14 of the compartment-section 1 forms a side to divide such apartment into two rooms, one of which rooms 15 (see Fig. II) is thereby adapted for a living-room, bed-room, library, or back parlor, while 100 the other room 16 is adapted for toilet, bath-room, bed-room, and kitchen.

105 The bed 12, which is pivoted by pivots 17 in the bed-holding compartment 8, is furnished with a shelf 18 to form a leg for the bed when the same is lowered. The bottom 19 of said bed is formed to close the front of the bed-holding compartment and to form an ornamental closure therefor, preferably to imitate the appearance of a mantel and fireplace. In this connection the shelf 18 serves as a mantelpiece when the bed is up and as a supporting-leg when the bed is down.

110 20 indicates a mirror for gracing the imitation fireplace 21 and also to serve the ordinary purposes of a mirror.

22 indicates a door to close the kitchen-compartment 9.

115 The upright curtain 13 is to be drawn out through an opening 23 in the face 14 of the 120 compartment-section 1. The curtain 13 is mounted on an upright spring-controlled roller 24, and its outer end is furnished with an upright rod or bar 25, by which the curtain can be held to form the desired partition.

125 26 indicates a secretary forming a door for the closet 7, and the pigeonholes and book-case of this secretary project into the closet 7 rearwardly of the face of the door to thereby be out of the way. The front 27 of the 130 secretary drops down, as indicated in Fig. VI, to form a desk and when raised effectually conceals the desk. The upper portion of the secretary is furnished with book-shelves 28,

extending rearwardly of the face of the door 26, so that the closet 7 serves as a receptacle for the book-shelves.

29 indicates pigeon-holes in the secretary, 5 to be covered by the desk-panel 27 in the ordinary way when said desk is raised.

The kitchen-compartment 9 is next to the toilet-compartment 6, and a portable window-seat 30 is furnished beneath its seat with a 10 chamber 31 to chamber the projecting end of the bath-tub 10 when the bath-tub is slid into the toilet-compartment 6. Said window-seat is formed next to the kitchen-compartment in an obtuse bend 32. The door 22 to close 15 the kitchen-compartment is formed in two leaves, 33 and 34, respectively, which are hinged together at 35, one of said leaves 33 being of a width of one side 36 of the bend 32 and being hinged to the inner face-wall 20 14 of the compartment-section at 37 and the other leaf 34 being hinged to the edge of said first-named leaf to bend against the outer side 38 of said bend, so that when the door is 25 fully opened it will fit closely against the window-seat.

39 indicates a gas-stove fastened to the first-named leaf 33 of the door, so that when both leaves of the door are fully opened, as stated above, the stove 39 will be brought out into the 30 room 16, which thereby is adapted for kitchen uses. The upright curtain 13 when outdrawn and fastened by the bar 25 will form a partition at right angles or at any other desired angle with the face 14 of the compartment-section. 35

The window-seat 30 is mounted on casters 40 and is furnished with a hinged back 41 to fold down upon the seat 42 of the window-seat.

40 43 indicates uprights having rearwardly sloping front faces, which support the back when it is raised.

44 indicates a drawer furnished with a wash-bowl 45 and a toilet-case 46. Said drawer 45 slides into the toilet-compartment 6.

47 indicates hinged faucets which fit against the wall of the toilet-compartment below the level of the upper edge of the hinged back 41 when the same is uplifted. The bottom of 50 the drawer 44 is at a height to come above the downfolded back 41 when the toilet-drawer is pulled out. When the toilet-drawer 44 is pushed back into place and the chair-back 41 raised, the toilet-drawer and hinged faucets 55 are thereby concealed.

48 indicates the middle walls of the double apartments.

49 indicates the double doors between the front apartment or front parlor and bed-room 60 50 and the rear apartment 51.

52 53 indicate fastenings for the upper and lower ends of the end bar 25 of the curtain. These fastenings may be of any suitable form. In the drawings the upper fastening 65 53 is a hook 52 to catch a ring 54 in the top of the bar 25, and the lower fastening is a socket

in the floor and into which the lower end of the curtain-bar will be inserted.

55 indicates a bed pivoted to move up into and down from a recess 56, cut off in a corner 70 of the front apartment 50 of each pair of apartments. The occupant of the front room 50 is thus supplied with a parlor, sitting-room, and bed-room, and by reason of the double doors 49 and the location of the curtain-bar at the parting thereof can readily gain access to the bath-room with privacy so far as the occupants of the bed-room 15 of the rear apartment are concerned. He can then open the door 49 and pass into and out 80 of the bath-room without disturbing the occupants of the bed-room 15. When the double doors are closed, the occupants of room 15 can go into and out of the bath-room with privacy by unfastening the curtain-bar from 85 the fastenings 52 and 53 and passing through and then refastening the curtain-bar to maintain privacy between the bath-room 16 and the bed-room 15.

57, 58, and 59, respectively, indicate the 90 vegetable-chest, ice-chest, and cedar chest formed between the floor-joists 60 of the compartment-section 1 and closed, respectively, by hinged sections 61, 62, and 63 of the floor of said compartment-section. 95

64 indicates the floor.

65 indicates a recess below the floor-level to chamber the end of the pivoted bed 12. The bottom of said bed is recessed at its inner end, as shown at 66, to allow the bed to stand 100 upright to form the fireplace face-wall 14 of the compartment-section and to cover the joint between it and the floor.

67 indicates a folding headboard carried by the inner end of the pivoted bed 12 to engage the well-wall 68, and thereby to be folded against the bedding to hold the same in place when the bed is upright. 105

69 indicates a valved ventilating-opening in the form of a door between the bed-holding compartment 8 and the bed and closet 110 ventilating well 70.

In practice when the bed is to be used the door 71 may be opened to ventilate the room or may be closed, if desired, and when the 115 bed is thrown up the door 71 may be allowed to remain open for the purpose of ventilating the bed-clothes. 72 indicates a like ventilating-door between the well 70 and the closet 7. 73 indicates a clothes-drying and kitchen-120 ventilating air-passage of the ventilating-well. 74 indicates a ventilating-door between this well and the kitchen-compartment.

75 indicates a swinging bracket mounted on a door 83 in the wall of the ventilating-well to swing out of and into said well. 76 is an olla or other water vessel on said swinging shelf or bracket to swing against the door and into the ventilator-well to cool the water or to swing into the kitchen for the convenience of the user. 125

77 indicates the sink, and 78 a dish drainer

and drier. These are located at the rear of the kitchen-compartment, and the water-cooler 76 on bracket 75 swings below the level of the bottom of the sink, so that the two will 5 not interfere with each other.

The bath-tub is furnished with a downwardly-extending drain-pipe 79, which discharges into a trough 80, which is connected through a trap 81 with a soil-pipe 82 in the 10 space *z* between the walls which form the partitions between the two compartment-sections, which stand back to back. This arrangement allows the bath-tub to be readily drawn out and pushed in without interfering with the 15 outlet therefrom and to allow the bath-tub to be emptied when fully drawn out.

85 indicates a cover for the dish drainer and drier.

86 indicates a valved drain-pipe leading 20 from the bottom of the dish-drainer 78 and connected with a drain-pipe 87, leading from the sink 77. 88 indicates the valve of the drain-pipe.

In practice when the housewife washes the 25 dishes she will place them upside down in the dish drainer and drier 78 and will fill said drainer and drier with boiling water, first having closed the valve 88 of the drain-pipe 86. Then the cover 85 will be closed and the dishes 30 allowed to thoroughly heat. When thoroughly hot, the valve 88 will be opened, allowing the water to drain off of the dishes, and the heat of the dishes will cause the water to evaporate, so that the dishes become perfectly dry, after which they will be taken out 35 and placed on the shelves 89.

90 indicates a tilting flour-bin in the kitchen.

91 indicates a table-forming panel on the inside face of the leaf 34 of the kitchen-door.

40 92 indicates a recess in the door to allow the table-forming panel 91 to be caught upon a hook 93, fastened to the door 22.

94 indicates a hook projecting from one side of the table-top 91 to hook into a recess 95 in

45 the stand-forming back 96 of the table-forming chair 97. When it is desired to use the rear apartment as a dining-room, the lower end of the back 96 of the table-forming chair 97 will be brought against the panel 91 under-

50neath the hook 94, which is placed so that when the panel 91 is in normal position and said chair-back is folded down upon the chair the lower end of the chair-back 96 will be slightly above the level at which the hook 94

55 of the panel stands when the panel is in normal position. Then by lowering the back 96 onto the chair the chair-back 96 will lift the panel 91 and allow it to tilt forward off of the hook 93 and to be brought into horizontal po-

60sition to form a dining-table, as shown in Fig. XII.

39 indicates a gas-stove fastened on the subleaf 33 of the kitchen-door and adapted to fit in the corner of the kitchen when said subleaf 65 33 is closed and to be drawn out into the apartment 51 when said subleaf of the kitchen-door is opened.

It is to be understood that my invention is not limited to the use of the hinged stand-top 96, for the same function as that performed by it can be performed by tilting the stand-top in any manner. With an ordinary stand, (not shown,) for instance, the whole stand could readily be tilted to bring the edge of the stand-top under the hooks 94, and by 70 then lowering the stand to normal position the panel will be lifted by such stand, as in case of the hinged stand-top 96 shown in the drawings.

Referring to Fig. I, 100 indicates a building having four outside walls 101 102 103 104, and on each floor of the building two rows *a b* of double apartments, each of said double apartments *c* comprising a front and back parlor, the rear wall of the back parlor being 80 formed by the face-wall 14 of a compartment-section 1. The suites of double apartments *c* are arranged in pairs and the compartment-sections 1 of the double apartments of each pair are arranged together back to back, and 85 the soil-pipes 82 for the two suites of double apartments forming each pair are located in the dead-wall *d* between the suites of each pair. *e* indicates hallways separated from each other by a partition-wall *f*. *g* indicates 90 doors opening from said hallways. *h* indicates 95 windows for the apartments.

The sink, dish-drainer, and the drain-pipes therefor will be all connected together and manufactured ready to be set into place in 100 the kitchen-compartment.

It is to be understood that the apartments may be finished in any desired style; but that since there are only two rooms involved with the conveniences of six rooms the expense of finishing can be multiplied by three 105 without any actual increase in the cost of the finishing over that which would be required for six rooms; but when in addition to this economy the cost of building the structure 110 for the six rooms is taken into consideration and the cost of the land covered by said six rooms it is readily seen that the furnishings for the two rooms may be superbly elegant without in any manner approaching the 115 initial cost of the six rooms.

Referring to Fig. XVI, 52 indicates a hook opening at one side. 53 indicates a socket in the floor. The bar or rod 25 of the curtain will be preferably a three-eighths steel rod 120 and is held in place by simply inserting the lower end thereof, which projects below the curtain, into the socket 53 and the upper end thereof, which projects above the curtain, into the hook. The spring-operated roller will 125 hold the curtain taut to form the partition.

k indicates foraminous shelves formed of wire-netting arranged in the ventilating-well 73, which opens from the kitchen-compartment, the purpose of this being to hold butter 130 and other substances which it is desired to cool. It is to be understood that the ventilating-wells will be appropriately connected with inlets and outlets and that cowls (not shown)

will be appropriately arranged to produce a draft through said wells. *m* indicates hooks in the bed-ventilating flue 70 of the ventilating-well for the support of cloths and clothes, 5 which may be hung into said well for drying purposes or for airing.

The stove 39 will be supplied with fuel through a flexible tube or other pipe (not shown) and may be applied to heat a small 10 water-heater *n*, which is fastened to the wall of the kitchen-compartment.

What I claim, and desire to secure by Letters Patent of the United States, is—

1. A compartment-section for a house comprising a case divided by partitions to form at one end a toilet-compartment, at the other end a secretary and clothes and cot storing closet; and between the toilet-compartment and the closet, a bed-holding compartment, 15 and a kitchen and pantry compartment; a bath-tub of greater length than the depth of the toilet-compartment, mounted in said toilet-compartment to slide out and in; a combined clothes-rack and cot-frame interchangeably 20 mounted in the closet and on the top of the outdrawn bath-tub for interchangeable use as a clothes-rack and bed; a bed pivoted in the bed-holding compartment; an upright curtain mounted in the compartment-section, 25 to be drawn out to form a partition in any apartment of which the face of the compartment-section forms a side, to divide such apartment into two rooms, one of which rooms is thereby adapted for a bed-room, living- 30 room and back parlor, while the other room is adapted for a toilet, bath-room and bed-room.

2. A compartment-section for a house, comprising a case divided by partitions to form 40 at one end a toilet-compartment, at the other end a secretary and clothes and cot storing closet, and between the toilet-compartment and the closet, a bed-holding compartment and a kitchen and pantry compartment; a 45 bath-tub of greater length than the depth of the toilet-compartment mounted in said toilet-compartment to slide out and in; a combined clothes-rack and cot-frame interchangeably mounted in the closet and on the top of the 50 outdrawn bath-tub for interchangeable use as a clothes-rack and cot-bed; a bed pivoted to fold into the bed-holding compartment and furnished with a shelf to form a leg for the bed when the same is lowered, the bottom of 55 said bed being formed to close the front of the bed-holding compartment and to imitate a fireplace; a door to close the kitchen-compartment; and an upright curtain mounted in the kitchen-compartment to be drawn out 60 through an opening in said compartment-section to form a partition in any apartment of which the face of the compartment-section forms a side.

3. A compartment-section for a house, comprising a case divided by partitions to form 65 at one end a toilet-compartment and at the other end a closet; a secretary forming a door

for the closet; a bed-holding compartment next to the closet; a bed pivoted to fold into the bed-holding compartment and to form an ornamental closure for the front of said compartment; a kitchen-compartment; a bath-tub of greater length than the depth of the toilet-compartment, mounted in said toilet-compartment to slide out and in; a portable 70 window-seat furnished with a chamber to chamber the projecting end of the bath-tub when the bath-tub is slid into the toilet-compartment, said window-seat being formed next to the kitchen-compartment in an obtuse 75 bend; a door to close the kitchen-compartment and formed in two leaves hinged together, one of said leaves being of the width of one side of said bend, and the other leaf hinged to the edge of said first-named leaf; 80 a stove fastened to said first-named leaf to be swung into and out of the kitchen-compartment; and an upright curtain mounted in the kitchen-compartment and adapted to be outdrawn to form a partition in any apartment of which the face of the compartment-section forms a side.

4. A compartment-section for a house, comprising a case divided by partitions to form at one portion a toilet-compartment and at 95 another portion a bed-holding compartment; a bed pivoted to fold into the bed-holding compartment; toilet appliances to slide into the toilet-compartment; and an upright curtain mounted in said compartment-section, 100 to be outdrawn therefrom to form a partition between the toilet and the bed in any apartment of which the face of the compartment-section forms a side.

5. A compartment-section for a house, comprising a case divided by partitions to form at one part a bed-holding compartment and at another part a kitchen-compartment; a bed pivoted to fold into the bed-holding compartment and to form an ornamental closure 110 therefor; a door to close the opening into the kitchen-compartment; and an upright curtain mounted in the compartment-section to be outdrawn therefrom to form a partition between the bed and the kitchen-compartment 115 in any apartment of which the face of the compartment-section forms a side.

6. A compartment-section for a house, comprising a case divided by partitions to form a bed-holding compartment and a kitchen-compartment adjacent to each other; and a 120 ventilating-well behind the bed-holding compartment, divided into two upright air-passages; an opening leading into one of said passages from the kitchen-compartment, said 125 passages being close to the bed-holding compartment, an opening being provided between the bed-holding compartment and the other air-passage; means for closing said last-named opening; and a bed pivoted to fold into the bed-holding compartment to form an ornamental closure for said compartment.

7. A compartment-section for a house, comprising a case divided by partitions to form

- a bed-holding compartment and a closet-compartment adjacent thereto; a ventilating-well behind the bed-holding compartment, openings being provided between the ventilating-well and the bed-holding compartment and closet respectively; means for closing said openings; a door for the closet; and a bed pivoted to fold into the bed-holding compartment to form a closure for the same.
10. An apartment-house comprising walls to form one or more pairs of double apartments, the double apartments of each pair being furnished respectively at one end with a compartment-section, the apartments of each pair of double apartments being arranged with their compartment-sections abutting; plumbing connections between the abutting compartment-sections; and plumbing-fixtures in said compartment-sections respectively and connected with said plumbing connections.
15. An apartment-house comprising walls to form a double apartment and furnished at one end with a main partition to set off a compartment-section at that end of said double apartment; a plurality of subpartitions extending from said main partition to the end wall of the compartment to form with said partition and the walls of the compartment-section set off by said partition, a closet, a bed-holder, a pantry and kitchen, and a bath-tub and washstand holder; a bath-tub and a washbowl and fixtures in said bath-tub and washstand holder and a curtain in the compartment-section between the bed-holder and the bath-tub and washstand holder to extend across the apartment, substantially as and for the purpose set forth.
20. A house, comprising the walls of an apartment, a cross-partition and subpartitions at one end of said apartment to form a closet and bed-storing compartment, a bed-holder, a kitchen and pantry compartment, and a toilet-compartment; a bed pivoted in the bed-holder and having its under side formed with
- 25 a shelf projection to constitute a support for the bed when the bed is down, and a shelf when the bed is folded up into the holder; a ventilating-well being formed between the bed-holder and the end wall of the apartment;
- 30 a vertical partition dividing said well into two upright passages; valved openings being provided between one of said passages and the closet-compartment and the bed-holder respectively; a valved opening being provided between the other flue and the kitchen and pantry compartment; a door for the closet formed in a secretary; a door for the kitchen-compartment; a bath-tub for the bath-tub holder; an upright spring-controlled curtain at the compartment-forming partition; and means for fastening the free end of said curtain in upright position at the opposite wall of the apartment.
35. An apartment-house comprising walls to form an apartment; a cross-partition and subpartitions at one end of said apartment to

form a closet and bed-storing compartment, a bed-holder, a kitchen and a pantry compartment, and a toilet-compartment; a bed pivoted in the bed-holder and having its under side formed with a shelf projection to constitute a support for the bed when the bed is down and a shelf when the bed is folded into the holder; a ventilating-well being formed between the bed-holder and the end wall of the apartment; a vertical partition dividing said well into two upright passages, valved openings being provided between one of said passages and the closet-compartment and the bed-holder respectively; means in the upright passage which communicates with the closet-compartment for holding clothes for drying; perforated shelves in the other passage which communicates with the kitchen-compartment; a swinging bracket mounted to swing into and out of the well from and into the kitchen-compartment; a bath-tub mounted to slide into and out of the toilet-compartment; a cot-frame capable of being stored in the closet-compartment and adapted to be applied to the top of the bath-tub when drawn out and furnished at one end with a folding leg to rest upon the floor to support the foot of the cot-bed, said cot-bed being furnished on its under side with hooks for supporting clothes of the cot-bed to air the same when in the closet.

12. In an apartment-house, a double apartment furnished at one side with a partition forming a number of compartments; a curtain to temporarily separate one of the apartments into two rooms; a bed-holder and bed being in one of said rooms; a movable bath-tub in the other of said rooms adapted to move into and out of one of the compartments at the end of said room; plumbing appliances to receive the discharge from the bath-tub and to allow the bath-tub to move freely; and a seat to fit over the outer end of said bath-tub to conceal the same.

13. In an apartment-house, a row of compartments, one of said compartments being arranged to receive a movable bath-tub and another of said compartments being provided with a receptacle for a cot-bed frame; a bath-tub in the bath-tub compartment and the cot-bed frame interchangeably adapted for the cot-bed-frame compartment and for the bath-tub, said frame being adapted to fit upon the bath-tub when the same is drawn out from its compartment.

14. An apartment-house furnished with walls to form an apartment and at one end of said apartment, partitions and subpartitions to form a plurality of compartments, one of said compartments forming a bed-holder and behind said compartment, an air-passage; a valved opening between the bed-holder compartment and the air-passage; and a bed-frame fitting in the bed-holder and having its bottom formed in an imitation mantel-piece, the shelf of which is adapted to form

a support for the bed when the same is lowered into position for use; the bottom of said bed forming a closure for the said opening.

15. An apartment-house furnished at one end of one of its apartments with a bath-tub-holding compartment; a bath-tub to slide into and out of such compartment and being of greater length than the chamber of the compartment; a sliding case furnished with a washbowl and sliding into said compartment above the bath-tub; water-supplying fixtures in the wall of the bath-tub compartment above the sliding case; a chair formed with a chamber beneath its seat closed at front and side to chamber the protruding end of the bath-tub; and having a back hinged to said seat and arranged to stand up to conceal the drawer and water-fixtures, and to fold down upon the bath-tub to allow the case to be slid out.

20. 16. In an apartment-house, a compartment-section furnished with a kitchen-compartment and a ventilating-well; a door for the ventilating-well; a swinging bracket on said door; and a water-holder on said swinging bracket.

17. In an apartment-house, a compartment-section furnished with a ventilating-well and a bed-holder compartment in front of said well; a door communicating between the bed-holding compartment and the well; and a bed pivoted in said bed-holder to fold up and close the opening thereof.

18. In an apartment-house, a bed-holding compartment having an extension below the level of the floor of the compartment; and a bed pivoted in said compartment to extend into said recess when brought into upright position.

19. The combination with the apartment-floor and the bed-holding compartment extending above and below said floor, of a bed pivoted to swing into and out of said compartment and furnished in its bottom with a recess to receive the edge of the floor to cover the joint between the floor and the bed when the bed is in upright position.

20. In an apartment-house, a bath-tub-receiving compartment; a trough below said compartment; a trap and sewer connections leading from said trough; and a bath-tub to slide in said compartment above said trough

and furnished with a discharge-pipe to discharge into said trough.

21. In an apartment-house, a ventilating-well furnished with foraminated shelves, substantially as and for the purpose set forth.

22. In an apartment-house, a compartment-section forming one end of an apartment and provided with a kitchen-compartment and a double-leafed door for closing said compartment, and a stove fastened to the subleaf of said door to be swung into and out of the kitchen-compartment.

23. In an apartment-house, a door closing one of the compartments and furnished on its inner side with a removable panel and a table with a hinged top of smaller size than the removable panel of the door, and means for connecting the table-top and the door-panel to thereby form a table of larger dimensions.

24. A door furnished with a panel-holder; a removable panel in said holder furnished with a hook; means for retaining said panel in said panel-holder; a table furnished with a hinged top of smaller dimensions than the panel, and also furnished with seats to receive the hooks of the panel; the several parts being constructed and arranged to bring said seats below said hooks to receive the same when the table-top is tilted and to lift the panel from the holder when the table-top is brought to horizontal position.

25. The combination of an upright panel-holder; a panel for said holder; a table furnished with a hinged top; and an attachment for connecting said hinged top with the panel to lift the same from the holder, substantially as set forth.

26. The combination of a panel-holder; a panel for said holder; a stand; and an attachment for connecting the top of the stand with the panel to lift the same from the holder.

In testimony whereof I have signed my name to this specification, in the presence of two subscribing witnesses, at Los Angeles, California, this 23d day of May, 1901.

W. C. JAMES.
